UNITED STATES PATENT OFFICE.

CHARLES ARTHUR FOGARTY, OF NEW YORK, N. Y.

BRUSH.

1,138,466.

Specification of Letters Patent.

Patented May 4, 1915.

Application filed April 29, 1914. Serial No. 835,152.

To all whom it may concern:

Be it known that I, CHARLES ARTHUR FOGARTY, a citizen of the United States, and a resident of the city of New York, borough 5 of Brooklyn, in the county of Kings and State of New York, have invented a new and Improved Brush, of which the following is a full, clear, and exact description.

My invention relates to brushes, and an 10 object thereof is to provide a simple, convenient, inexpensive and neat looking brush in which the bristles of the stock are doubled up so that the same cannot fall out from the support therefor.

15 Another object of the invention is to provide a brush which reinforces the stock at the handle and thereby stiffens it.

I attain these objects by the structure illustrated in the accompanying drawings 20 forming a part of the specification, in which similar characters of reference indicate corresponding parts in all the views and wherein—

Figure 1 is a vertical section through a 25 brush embodying my invention; Fig. 2 is an elevation of same partly in section showing certain details of construction; Fig. 3 is an elevation of the bristle support before the bristles are attached thereto; Fig. 4 is a 30 modified structure of the bristle carrier; Fig. 5 is a section on line 5—5, Fig. 2; Fig. 6 is a section on line 6—6, Fig. 2.

In brushes where a doubled-up stock of bristles is used, the stock must be clamped 35 below the loop so as to maintain the same in place; and to prevent the turning of the stock of bristles in the loop, generally an exterior casing is put over it. This structure is, in general, not satisfactory, as there is no 40 reinforcement within the body of the bristles. To obviate this defect, I have provided the bristle carrier with an extension, which may be a part of the bristle carrier or may be rigidly secured thereto.

45 Referring to the drawings, 7 represents a bristle carrier, which is preferably made of wire, the loop 8 of which is adapted to be engaged by the stock which is doubled up about the loop. The loop has an extension 9 50 which is preferably widened at the end 10. The loop is normally open; and after the stock has been inserted therethrough, the open end of the loop is closed by twisting the wire forming the loop so that a stem 11 is

formed. This closing of the loop tightens 55 the doubled-up stock in the loop with the extension 10 positioned between the bristles of the stock, as shown in Figs. 1 and 5. The bristles of the stock are then engaged exteriorly by an annular member 12, which is 60 then flattened in the plane of the loop to clamp the stock and the extension 10. This clamping of the stock and the extension prevents the movement of the bristles within the loop. It, furthermore, stiffens the bristles adjacent the loop and, therefore, adds to the rigidity of the stock of bristles adjacent the bristle carrier 7. After the stock has been clamped as described, the stem 11 65 of the bristle carrier 7 is made to pass 70 through a sleeve 13, of any suitable material, and the ends of the wires forming the stem are bent over so as to lock the bristle carrier to the sleeve. The sleeve 13 is also provided with a casing 14 adapted to cover the 75 clamping member 12 and also the part of the loop exterior of the bristles. A suitable handle 15 can then be secured to the sleeve as shown in Figs. 1 and 2.

In the modified structure of my bristle 80 holder as shown in Fig. 4, the handle 16 for the brush is formed integral with the loop 8', in which case the extension 9' remains open until the bristles are placed into the loop, when the same is closed, as shown in 85 Fig. 4, with the lower part 10' forming the engagement for the purpose described. It is self-evident that the length of the handle 16 can be varied to suit different conditions. The handle shown in Figs. 1 and 2 is mainly 90 intended for a better class of goods.

It is evident that various changes might be made and modifications resorted to in the construction and arrangement of the parts described without departing from the 95 spirit and scope of my invention; hence, I do not wish to limit myself to the exact construction shown.

Throughout the entire specification the word "bristles" has been used as a general 100 term for horse hair and brush fiber or any other suitable material for brushes of the class described.

Having thus described my invention, I claim as new and desire to secure by Letters 105 Patent:

1. In a brush, a loop, doubled-up stock engaging the loop, said loop having an ex-

2
tension enlarged at the end thereof and positioned between the doubled-up stock by which the extension is covered, and a flattened annular member clamping the stock 5 to the extension.

2. In a brush, a bristle carrier comprising a shank, a loop and an extension from the loop, said extension and shank being on opposite sides of said loop and in alinement 10 with each other, said extension having an enlarged end, doubled-up stock engaging the loop and covering said extension, a flattened annular member clamping the stock to the extension and a handle associated 15 with the shank.

3. In a brush, a shank having a loop adapted to receive the stock, an extension from the loop in alinement with the shank, doubled-up stock engaging the loop and covering the extension, a flattened annular member engaging the stock exteriorly and clamping the same to the extension and a handle secured to the shank.

4. In a brush, a wire bristle carrier comprising a shank, a loop integral therewith and an extension from the loop having an enlarged end, said shank and extension being on opposite sides of the loop and in alinement with each other; doubled-up stock engaged in the loop and covering the extension; a flattened annular member engaging exteriorly the stock and clamping the same 30

to the extension and a handle secured to the shank.

5. In a brush, a wire loop having an extension integral therewith, said extension having an enlarged end, said loop having also a stem on the opposite side from the extension and in alinement therewith; doubled-up stock engaging the loop and covering said extension; a flattened annular member engaging exteriorly the stock and clamping the same to the extension; a handle associated with the stem; and a cover for the loop and annular member associated with 45 said handle.

6. In a brush, a bristle carrier formed of a single wire shaped to form a loop having an extension enlarged at one end, and a shank having a handle positioned at the 50 other side of the loop and in alinement with said extension, said extension adapted to form a reinforcement for doubled stock about the loop, substantially as and for the purpose set forth.

55
In testimony whereof I have signed my name to this specification in the presence of the subscribing witnesses.

CHARLES ARTHUR FOGARTY.
